UNITED STATES PATENT OFFICE.

CONRAD A. WINTERS, OF ANACONDA, MONTANA.

MEANS FOR THAWING OUT SEWERS.

1,292,941.

Specification of Letters Patent.

Patented Jan. 28, 1919.

Application filed November 10, 1917. Serial No. 201,352.

To all whom it may concern:

Be it known that I, CONRAD A. WINTERS, a citizen of the United States, residing at Anaconda, in the county of Deerlodge and 5 State of Montana, have invented a new and useful Means for Thawing Out Sewers, of which the following is a specification.

This invention has reference to means for thawing out sewers, and its object is to 10 provide a permanent installation whereby the melting of frozen accumulations of water in catch basins may be accomplished.

In sewer systems for streets, it is customary to lead the gutters into catch basins, 15 and the latter are connected to the main sewer. In cold climates, it frequently happens that the accumulations of water in the catch basins freeze, with the result that the catch basins become choked with ice which 20 may completely close the leads to the main sewer, so that the catch basins will fill up and overflow to the detriment of the street.

In accordance with the invention, each 25 catch basin is traversed by a steam pipe which may in turn be carried through the curbing to the top of the latter to be there accessible and which may be there protected by a suitable cover plate. The steam pipe is carried for a suitable distance into the 30 branch sewer leading to the main sewer, so that when the need occurs, a steam hose may be connected to the upper end of the steam pipe and steam be forced into the branch pipe, thus heating the steam pipe 35 and causing the melting of the ice in its immediate neighborhood, so that the steam can return through the melted passageway into the catch basin and cause the rapid melting of the ice already accumulated 40 therein. In this way, frozen catch basins may be thawed out in a relatively short time.

The invention will be best understood 45 from a consideration of the following detailed description, taken in connection with the accompanying drawing forming part of this specification, with the further understanding that, while the drawing shows a practical form of the invention, the latter 50 is not confined to any strict conformity with the showing of the drawings but may be changed and modified so long as such changes and modifications come within the scope of the appended claims.

55 In the drawing:

Figure 1 is a plan view of a street cross-

ing showing a sewer system and a series of catch basins at the street corners;

Fig. 2 is a vertical section through a 60 catch basin and adjacent portions of the street;

Fig. 3 is a view of a cover box for the accessible end of the steam pipe and shown on a larger scale than in the other drawings.

Referring to the drawing, there are shown 65 two intersecting streets A and B, the showing being in a manner schematic and without any attempt at accuracy of proportions. The streets are indicated as provided with a curbing 1 which, in the particular showing of the drawings, and more especially in Fig. 2, is indicated as constructed of concrete.

At the corners of the streets there are provided 70 catch basins 2, the showing of the drawings assuming that four such catch basins are provided, but it will be understood that any appropriate number may be employed. Each catch basin, which may be formed of concrete or in any other suitable 75 manner, has an outlet pipe 3 leading therefrom to another catch basin 4 opening into a main sewer 5, which in turn may lead to a suitable point of disposal. The catch basin at the main sewer is accessible through a 80 manhole provided with a cover 6, but this particular feature does not necessarily enter 85 into the invention.

Each catch basin 2 has a top frame 7 on 90 which there is located a perforated plate 8 for the intake for water flowing from the streets, as is customary. The sewer arrangement illustrated in the drawings is to be taken as typical of any suitable sewer arrangement for the disposal of surplus water, 95 especially storm water and the like.

Each catch basin 2 has its outlet pipe 3 at 100 a suitable distance above the bottom for retaining material which may flow into the catch basin so that it may not reach the main sewer and clog it, it being the custom to clean out the catch basins from time to time. Within each catch basin 2 and entering the same at a high point is a pipe 9, having at its upper end a continuation 10 leading upwardly through the curb 1 and terminating in the threaded extremity 11 or in any other manner permitting the ready attachment thereto of a steam pipe, such as a steam hose. In order to protect the upper end of 110 the pipe 10 from ordinary access, the threaded end 11 of the pipe is carried into a box

12 set in the curb 1 flush with the top thereof or nearly so. The box 12 is provided with a solid cover 13 which may be removed when access to the pipe 10 is desired.

5. At the lower end of the pipe 9 there is a branch 14 leading into the pipe 3 and terminating in a nozzle 15, although the nozzle may be omitted if desired.

Where weather conditions cause water to 10 flow along the roadway into the catch basins 2 through the perforated covers 8 and when the weather is cold enough to cause the water to freeze in the catch basins, ice may accumulate therein until it ultimately fills the 15 catch basin above the outlet pipe 3 so that the accumulation of ice may finally become so great as to fill the catch basin and cause overflow thereof and the formation of ice in the roadway. To prevent such condition occurring, the catch basins may be thawed out 20 from time to time by gaining access to the pipes 10 on the removal of the covers 13, and then by connecting a source of steam supply to the pipe end 11, steam may be 25 caused to flow out of the nozzle 15 into the pipe 3. If the accumulation of ice within the catch basin be so high as to clog up the pipe 3 at the catch basin, the steam will simply flow to the sewer 5, but the heat of the 30 steam will melt ice surrounding the pipes 9 and 14 until there is a passageway about the pipe into the catch basin and quickly melt ice therein until the catch basin is freed and all immediate danger of clogging is prevented.

The invention provides an ever present means in the catch basins for heating the ice from within the body of the latter, thus quickly disintegrating the ice and causing it 40 to melt much faster than would be the case if the steam were directed against the outer surface only of the ice.

By placing the pipe 10 within the curbing 1, it is not only well protected from injury, but is in a convenient location for access, being at all times protected by the cover plate 13.

What is claimed is:

1. In street construction, the combination 50 with a catch basin having sewer connections,

of a steam pipe accessible at the street and extending through the catch basin and opening into the sewer connections.

2. In street construction, a catch basin having sewer connections, curbing adjacent 55 to the catch basin, and a pipe extending through the curbing to the top thereof and there accessible and entering the catch basin near the top of the latter and extending through the catch basin to a point opposite 60 the sewer connections of the latter and thence across the catch basin into the sewer connections for conducting steam from a source thereof connected to the accessible end of the pipe into the sewer connections. 65

3. In street construction, a catch basin having a sewer connection, a curbing adjacent to the catch basin and having a covered box at its upper end, and a pipe having one end located in the box and there provided 70 with means for connecting it with a steam supply, said pipe extending through the curbing to a point below the top of the catch basin and there entering the latter and extended through the catch basin into the 75 connections from the catch basin to the sewer and there open.

4. In street construction, a catch basin provided with a sewer connection, curbing adjacent to the catch basin, a pipe extending 80 through the curbing and into the catch basin at a high point of the latter, thence down that side of the catch basin adjacent to the curbing and thence across the catch basin into the sewer connection and opening 85 into the latter, and a compartment in the upper part of the curbing receiving the pipe and provided with a cover for normally protecting the pipe against access, said pipe having means at the end within the compartment for the reception of a connection to a steam supply. 90

In testimony, that I claim the foregoing as my own, I have hereto affixed my signature in the presence of two witnesses.

CONRAD A. WINTERS.
